(57) **CLAIM**

The ornamental design for a waterpark float, as shown and described.

DESCRIPTION

FIG. 1 is a front perspective view of a first embodiment of the waterpark float.

FIG. 2 is a front view of the first embodiment of the waterpark float.

FIG. 3 is a rear view of the first embodiment of the waterpark float.

FIG. 4 is a side view of the first embodiment of the waterpark float.

FIG. 5 is another side view of the first embodiment of the waterpark float.

FIG. 6 is a top view of the first embodiment of the waterpark float.

FIG. 7 is a bottom view of the first embodiment of the waterpark float.

FIG. 8 is a front perspective view of a second embodiment of the waterpark float.

FIG. 9 is a front view of the second embodiment of the waterpark float.

FIG. 10 is a rear view of the second embodiment of the waterpark float.

FIG. 11 is a side view of the second embodiment of the waterpark float.

FIG. 12 is another side view of the second embodiment of the waterpark float.

FIG. 13 is a top view of the second embodiment of the waterpark float; and,

FIG. 14 is a bottom view of the second embodiment of the waterpark float.

The broken-outlined portion of the bottom of the waterpark float in FIG. 7 is included to illustrate environment but forms no part of the first embodiment of the claimed design.

The showing of evenly-spaced broken lines is included for the purpose of illustrating environmental structure and forms no part of the claimed design. The evenly-spaced broken lines in FIGS. 7 & 14 represent boundary lines and do not form part of the claimed design.

(Continued)

The broken-line features of the waterpark float in FIGS. 8-13, and the broken-outlined portion of the bottom of the waterpark float in FIG. 14, are included to illustrate environment but form no part of the second embodiment of the claimed design.
